Inventor

CARL H. ZWERMANN.

UNITED STATES PATENT OFFICE.

CARL H. ZWERMANN, OF KALAMAZOO, MICHIGAN.

TRUCK FOR TUNNEL-KILNS.

1,306,160.

Specification of Letters Patent. Patented June 10, 1919.

Application filed February 16, 1918. Serial No. 217,702.

To all whom it may concern:

Be it known that I, CARL H. ZWERMANN, a citizen of the United States, residing at Kalamazoo, Michigan, have invented certain new and useful Improvements in Trucks for Tunnel-Kilns, of which the following is a specification.

This invention relates to improvements in trucks for tunnel kilns.

10 The objects of the invention are:

First, to provide a simple, effective and compact construction of such truck.

Second, to provide an improved construction of truck wherein it will not be necessary 15 to renew the fire clay, tile or brick, or rebuild the same at frequent intervals.

Objects which relate to details and to economies of construction will definitely appear from the detailed description to follow.

20 I accomplish the objects of my invention by the devices and means described in the following specification. The invention is clearly defined and pointed out in the claims.

A structure which is a preferred embodiment of my invention is fully illustrated in the accompanying drawing forming a part of this specification, in which:

25 Figure I is a rear end elevational view of the truck embodying the features of my invention.

Fig. II is a central detail sectional elevation, taken on a line corresponding to line 2—2 of Fig. I.

30 Fig. III is a detail plan view of the structure illustrated in Fig. I.

Fig. IV is a detail perspective view of one of the fire clay bricks or tiles forming the fireproof platform or body of the truck.

35 In the drawings, similar numerals of reference refer to similar parts throughout the several views.

Considering the lettered parts of the drawing, 1, 1 are the side channel bars of a truck connected to form a frame by the 40 channel pieces 2, 2. These are supported on truck wheels 3, 3' one of which is grooved to properly engage the rail and the other of which is flat on its periphery to permit of expansion and contraction when subjected to 45 the heat of the kiln.

50 4 is the axle carried by the said truck wheels. 5 is a cast iron bumper secured to the front and rear cross channel bars centrally to save the other parts of the truck 55 from injury.

56 6 is a sheet metal platform disposed upon

the top of the angle frame. On this platform are disposed transverse I-beams 7, 7 with channel beams 7' at each end to accommodate the attachment of the front and rear 60 end plates 10. The space between the I-beams 7 is filled with kieselguhr 8.

The side plates 9 are secured in any suitable way to the sides of the truck and extend down to form flanges for engagement with 65 the usual sand troughs disposed within the tunnel-kiln. Front and rear end plates 10 are provided as indicated.

On the I-beams 7, 7' are a series of fire brick or tiles 11, 12, 12 and 13, preferably made 70 in three overlapping sections, the upper ends of which are shouldered to interlock the one with the other. The rear row 11 of these bricks, that is the row at the rear end of the truck, is provided with a transverse channel 75 11' within which is disposed the clamping plate 15, through which are disposed the clamping bolts 14, which extend through the brick from the front to rear of the truck.

The front row of bricks 13 is provided 80 with a transverse channel 13' within which is disposed an angle bar 16 having its forward edge projecting beyond the front of the truck and in position to enter into the channel 11' of the next succeeding brick. 85

This channel bar 16 is covered with layers of asbestos to protect it from the undue heat. It will be seen that the longitudinal bolts through these bricks anchor the same securely together and owing to the shouldered 90 arrangement at the upper part, the accumulations of dust and sand cannot enter between the brick and cause them to separate.

The upper deck of the truck can be easily kept entirely clean and thereby all necessity 95 for relaying the fire brick in the platform is avoided and the truck can be used continuously until worn out. However, when the bricks are worn out they can be very readily replaced by withdrawing the bolts. As 100 the fire brick form a very substantial protection for the metal parts of the truck below, it is thus possible to keep the truck in use for a long time by merely renewing the upper deck when it has become worn out or 105 burned out or for other reasons rendered unusable.

I desire to state that the details of the structure here illustrated can be considerably modified without departing from my invention which is clearly pointed out in the appended claims.

Having thus described my invention, what I claim as new and desire to secure by Letters Patent is:

1. In a kiln truck, the combination of the truck structure, a platform of sheet metal thereon, transverse beams upon the said platform with kieselguhr therebetween, tile in sections resting upon the said I-beams and having shouldered projecting parts in interlocking at their upper surfaces, and provided with channels at front and rear, longitudinal bolts disposed through the said tiles to retain the same, a flat plate disposed in one channel and an angle bar disposed in the other channel with a projecting edge, and an asbestos layer on the said projecting edge, all coacting substantially as described for the purpose specified.
2. In a kiln truck, the combination of the truck structure, a platform of sheet metal thereon, transverse beams upon the said platform with kieselguhr therebetween, tile in sections resting upon the said I-beams and having shouldered projecting parts in interlocking at their upper surfaces, and bolts disposed through the said tiles to retain the same, all coacting substantially as described for the purpose specified.

3. In a tunnel-kiln truck structure the combination of a platform, shouldered tile disposed upon the said platform and interlocking with each other, longitudinal bolts therethrough, and a bar engaged by said bolts projecting from one end to form an interlock with the next succeeding truck, all coacting as specified.

4. In a truck for a tunnel kiln, the combination of transversely disposed tile with shouldered interlocking parts, longitudinal bolts therethrough, and bars disposed to receive the said bolts and form projections for interlocking of the trucks.

5. In a kiln truck, the combination of a truck structure, platform, spaced beams disposed upon said platform with kieselguhr therebetween, and shouldered tile disposed upon and supported by said bars and interlocking with each other, and means for securing said tile in position.

In witness whereof, I have hereunto set my hand and seal in the presence of two witnesses.

CARL H. ZWERMANN. [L. s.]
